CLAIM

The ornamental design for an electric vehicle charge port, as shown and described.

DESCRIPTION

FIG. 1 is a front view of an electric vehicle charge port showing our new design;

FIG. 2 is a front left perspective view thereof;

FIG. 3 is a front view thereof, shown in an environment of use;

FIG. 4 is a front right perspective view thereof;

FIG. 5 is a right view thereof;

FIG. 6 is a left view thereof;

FIG. 7 is a top view thereof;

FIG. 8 is a bottom view thereof; and,

FIG. 9 is a rear view thereof.

The portions of the motor vehicle exterior, shown overexposed in FIG. 3, are for the purpose of illustrating environment that forms no part of the claimed design.

1 Claim, 4 Drawing Sheets
